UNITED STATES PATENT OFFICE.

MORRIS W. LEDERER, OF DETROIT, MICHIGAN, ASSIGNOR TO LEDERER MANUFACTURING COMPANY, OF DETROIT, MICHIGAN, A CORPORATION OF MICHIGAN.

SHOPPING BAG.

Application filed April 17, 1924. Serial No. 707,033.

To all whom it may concern:

Be it known that I, MORRIS W. LEDERER, a citizen of the United States, and residing at Detroit, in the county of Wayne and State 5 of Michigan, have invented a new and Improved Shopping Bag, of which the following is a specification.

This invention relates to shopping bags and the object of the invention is to provide a shopping bag which may be folded 10 to appear like the usual handbag and which may be opened to provide a bag for carrying parcels for bulky articles and which will contain a considerable number of such articles.

Another object of the invention is to provide a shopping bag having a compartment 15 for carrying change, the said compartment being formed from a flap sewed to the interior of the bag and adapted to fasten over the bag when in the folded position to prevent the bag from unfolding.

Another object of the invention is to provide a flap sewed to the interior of one side 20 of the bag and extending over the other side of the bag the flap being provided with a snap for fastening to the exterior of the bag when folded beneath the flap so that the bag is thus held in the folded position 25 for carrying.

These objects and the several novel features of the invention are hereinafter more fully described and claimed and the preferred form of construction by which these 30 objects are attained is shown in the accompanying drawings in which—

Fig. 1 is a view of the bag in the open or unfolded position.

Fig. 2 is a section taken on line 2—2 of 40 Fig. 1.

Fig. 3 is a view of the bag in the folded position.

Fig. 4 is a section taken on line 4—4 of 45 Fig. 3.

The bag 1 may be made of imitation leather or any suitable fabric and is provided with an insert 2 in the bottom as shown in Fig. 2 which allows the bag to expand when filled with packages. This 50 bag is provided on the inner side thereof with a pocket formed by sewing a strip of material to the inner side of the bag by means of the stitching 4 which provides a pocket 5. The strip is provided with a

portion 6 of a snap fastener and a companion portion 7 is adapted to snap thereover and is secured in the side of the bag so that the two parts when snapped together close the pocket 5. The strip 3 is provided with an extending loose end or flap in which the portion 8 of a snap fastener is secured as shown in Fig. 2 and is adapted to fit the companion snap fastener portion 9 when the bag is folded, the snap fastener 9 being fastened in the same side of the bag 60 as the snap fastener portion 7. A handle 10 is secured to one side of the bag at the points 11 and 12 and a handle 13 is similarly secured to the opposite side of the bag.

To close the bag the edges thereof are 70 first folded toward the center on the dotted lines 14 and 15 and the bag thus folded is folded upwardly on the dotted lines 16, 17 and 18 thus bringing the fastener portion 9 beneath the fastener portion 8 and 75 allowing these two portions to be snapped together as shown in Figs. 3 and 4. It will be noted that when the bag is thus folded that the flap or strip 3 provides a cover for the folded edges of the bag and in the 80 folded position the snap fasteners 6 and 7 may be readily separated to allow access to the pocket 5 so that the pocket 5 is always easily accessible. When the bag is open in the position shown in Fig. 2 the 85 flap 3 may be tucked inside the bag so as to allow packages to be easily inserted in the bag and the flap may be readily inserted or withdrawn through the handle 13. To open the bag from the folded position shown in Fig. 4 it is only necessary 90 to unfasten the snap fastener portions 8 and 9 and shake the folds of the bag out and upon tucking the flap 3 into the interior of the bag the bag is ready for use. 95

If desired a snap fastener portion 19 may be secured in the bag beneath the handle 13 to provide a means after the bag has been filled with packages for closing the bag by extending the flap over and fastening the snap fastener portion 8 on the companion fastener portion 19.

From the foregoing description it becomes evident that the device is very simple and efficient in operation, is composed 105 of few parts and is of consequent low manufacturing cost, provides a small sized handbag when folded and a large sized bag for

carrying parcels when opened and provides a device which accomplishes the objects described.

Having thus fully described my invention, its utility and mode of operation, what I claim and desire to secure by Letters Patent of the United States is—

1. A shopping bag comprising an open ended bag provided with carrying handles on opposite sides of the opening, a flap sewed to the interior surface of one side of the bag between the ends of the respective handle to provide a pocket, a fastener portion on the flap and a companion fastener portion on the bag for closing the said pocket, the end of the flap being adapted to be extended through the handle on the opposite side of the bag and the bag being foldable beneath the said flap, a fastener portion secured to the bag and adapted to be brought beneath the flap when the bag is folded and a companion fastener portion secured in the end of the flap and providing a means for securing the bag in the folded position.
2. A shopping bag comprising an open

ended bag provided with carrying handles on opposite sides of the opening, a flap sewed to the interior surface of one side of the bag to provide a pocket, a fastener for closing the said pocket, the end of the flap being adapted to be extended over the opposite side of the bag to allow the bag to be folded therebeneath, and a fastener portion secured to the bag and adapted when the bag is folded to register beneath a companion fastener portion secured in the flap.

3. A shopping bag comprising an open ended bag provided with carrying handles on opposite sides of the opening, a flap sewed to the interior of one side of the bag to provide a pocket and adapted to be extended over the opposite side of the bag to allow the bag to be folded therebeneath, and means for securing the flap to the outer side of the bag therebeneath when folded to prevent the bag from unfolding.

In testimony whereof, I sign this specification.

MORRIS W. LEDERER.
